SPEED CONTROLLING AND SPEED MEASURING CENTRIFUGAL MECHANISM

Theodore H. Barth, New York, N. Y., assignor to
 Carl L. Norden, Inc., New York, N. Y., a corporation of New York

Application July 15, 1931. Serial No. 551,008

2 Claims. (Cl. 264—20)

My invention relates broadly to speed controlling and speed measuring centrifugal mechanism and more particularly to a compact construction of speed controlling mechanism capable of precision operation.

One of the objects of my invention is to provide a control mechanism having a high degree of precision for maintaining constant rotary motion.

10 Another object of my invention is to provide a compact construction of governing mechanism for rotary systems for insuring constant speed operation without employing bulky or complicated parts.

15 Still another object of my invention is to provide a simplified construction of centrifugal governing mechanism wherein a control member is moved in accordance with any tendency for variation in the speed of rotation for maintaining the rotating mechanism under constant speed.

Other and further objects of my invention reside in a precision type of centrifugal governing mechanism as set forth more fully in the specification hereinafter following by reference 25 to the accompanying drawings, in which:

Figure 1 is an end view of the speed controlling and speed measuring centrifugal mechanism with parts shown partially in cross-section for illustrating the assembly of the mechanism of my invention; Fig. 2 is a top plan view of the control knob of the centrifugal governing mechanism by which the operation of the centrifugal mechanism may be regulated for a certain predetermined speed; Fig. 3 is a diagrammatic 30 view showing the electrical circuit arrangement of the contact system operated by the governor mechanism of my invention for maintaining the speed of an electric motor constant; Fig. 4 is a longitudinal cross-sectional view taken along the line 4—4 of Fig. 1 through the centrifugal governor mechanism and the electric control system associated therewith; Fig. 5 is a lateral cross-sectional view taken through the governor mechanism on line 5—5 of Fig. 4; Fig. 6 is a 40 cross-sectional view through the governor housing on line 6—6 and showing parts of the governor mechanism in cross-section; Fig. 7 is a cross-sectional view taken through the control knob which is used for adjusting the operation 45 of the governor mechanism of my invention; Fig. 8 is an elevational view showing the adjustable limits which are permitted for shifting the position of the control knob with respect to the tension mechanism of the governor system; Fig. 50 9 is a view of one of the centrifugal arms em-

ployed in the governor mechanism; Figs. 10 and 11 show a modified form of contact system which may be used in the governor system of my invention.

The governor mechanism set forth herein has 60 been found capable of controlling and measuring rotary speeds more closely and over a larger range than devices heretofore known. The system of my invention employs a centrifugal device for the precision control of rotary motors. 65 The speed controlling or measuring mechanism of my invention permits the use of linear scales or linear functioning speed setting means, and the controlling or speed measuring can be done over the entire speed range accurately while the 70 centrifugal elements revolve.

My invention includes a pair of pivotally connected weighted arms which are rotated under control of a driven shaft. A tubular member on the frame of the governor extends in axial alignment with the driven shaft. A sleeve member is longitudinally adjustable along this tubular member under control of connecting links extending between the weighted arms and the sleeve member. A control rod or link extends through the tubular member and connects to a contact arm. The contact arm is journaled under adjustable spring tension which tension is controllable from a control knob which carries a calibrated scale. Selected tension may be placed 85 upon the contact arm to counterbalance predetermined centrifugal forces. The contact system which is made and broken by the movement of the contact arm is controlled at a rate dependent upon the centrifugal effort and the tension obtained by the adjustment of the control knob.

The leading characteristics of the system of my invention can be stated as follows. The only free and dynamically unbalanced forces of the revolving and active system are the centrifugal forces or couples to be measured or that are used for control purposes. The system may be set for normal speed as well as for any definite control speed or speed to be measured. The sleeve loading, counteracting and balancing the centrifugal forces or couples of the rotating system is done entirely from the outside, and variable from zero to the maximum over the entire range while the centrifugal end is rotating. The weighing or 95 governing is done close to a definite position of the rotating centrifugal parts in respect to their axis of rotation.

In case a sleeve in some form is used as part 100 of the rotating system, it rotates in or on a non- 110

rotating part, in order to obtain a maximum sensitivity. The external weighing or controlling devices can only be applied to centrifugal mechanism which permits the use of linear scales over the full range. The system can be used to control the speed of rotation of a conventional type of prime mover such as an electric motor. It can be used as a controlling device to limit the speed of rotation an acting torque causes, by means of a governing brake, or it can be used to control a variable speed gear to obtain closely a desired speed of rotation and for many other similar purposes.

The drawings illustrate the elements of my system in the simplest form, as applied to control the speed of an electric direct current motor, or servo motor. The centrifugal elements have, whether their speed of rotation is to be measured or whether they are to control to a definite speed, a fixed zero position in which they are disposed when the motor is running at its normal rate of speed. The total angular bar motion or axial sleeve motion is very small, hardly visible as such. Hence these governors can be either slightly static or astatic for this working position.

Referring now to the drawings which illustrate the elements of the system of my invention, Figs. 1-9 show a preferred form of the working parts as applied to the control of the speed of a direct current motor. Reference character 1 indicates a shaft which is an extension of the commutator end of the electric motor, the speed of which is to be controlled. The motor frame 2 confines radial end thrust bearing 3 in which the shaft 1 is rotatably mounted and this shaft carries a fork 5 which is secured by a pin 1a to turn with the shaft. Bars 4 are pivoted intermediate their ends upon a pin 6 carried by the fork in crossed relation to each other. The bars 4 are identical in construction and have their center of gravity near the intersection of the axis of rotation and the tilting axis 6. Links 7, 7 can also be considered centrifugal elements, connecting cross-bars 4, 4 to sleeve 8. This sleeve rotates and slides on bushing 10, fixed to housing 11 which in turn is fixed centrally to motor frame 2. Sleeve 8 also forms the outer race of a ball thrust bearing for connecting rod 9, the end of which is hardened and forms the inner race of the thrust bearing 9a which thus is self adjusting. The connection between cross bars 4, 4 and links 7, 7 is made by means of pins 12, 12 allowing angular movement between the cross-bars and the links. The sleeve 8 is rotated by one of the links 7, the other having side clearance of its cross bar. Links 7 are pivotally connected with sleeve 8 through pins 13.

Connecting rod 9 is hinged at 14a to control lever 14 fixed to shaft 16. This shaft is mounted on ball bearings 15 in housing 11, and axially fixed by follower 17 and nut 18.

A manually adjustable hand grip or control knob 22 is located adjacent one end of shaft 16 as shown. The knob end of shaft 16 is slotted at 16a to receive double spiral spring 19, the ends of which are fixed in spring case 20 at 20a which can be turned on a sleeve projection of housing 11, retained in place by guards 21 which also provide sufficient friction to prevent case 20 from turning. Control knob 22 is adjustably fixed to spring case 20 by means of screws 23, which operate through arcuate adjusting slots 22a in knob 22 as shown in Fig. 8. A knurled edge 22b is provided on the knob 22 adjacent the cylindrical surface which carries the calibrated band mem-

ber 22c. When knob 22 is turned clockwise, spring 19 is wound up exerting a turning moment on shaft 16 and lever 14 and a pulling force on connecting rod 9.

A non-conductor lever extension 24 fixed to lever 14 by screws 14a carries contact 25 while a non-conductor extension 26 fixed to housing 11 by means of screw 26a carries an aligned contact 27. Both contacts are adjustable as shown. The micrometer screws 25a and 27a insure an accurate setting of the contacts. Further adjustment can be made by moving micrometer screw 65 which forms a limiting stop with respect to insulated support 26.

Torque setting by turning the control knob 22 in the proper direction to tension the spring 19 tends to close contacts 25-27, supplying armature current to the motor of the shaft on which the governor bars are mounted. The armature and cross-bars will be accelerated until the centrifugal couples, expressed in sleeve-force, slightly exceed the connecting rod pull due to the spring moment, when the contact is broken. Lever 14 and all parts fixed to it, including rod 9, sleeve 8 and its ball bearing, balanced cross-bars 4 and links 7 for this normal position, so that gravity accelerations do not affect the speed at which the contact is broken for a definite spring torque.

Connection is made with movable contact 25 through lead 28 to terminal 28a. The lead 28 is sufficiently flexible so as not to introduce a disturbing moment in the movable system.

Referring to the wiring diagram of Fig. 3, when the armature contact is broken, friction and the work done by the motor will decelerate shaft 1 until spring 19 again closes the contacts 25-27. The motor is shown as including the armature 60 and field 61 connected with the supply circuit 62. The armature circuit is broken through contacts 25-27. Thus the motor armature receives a series of impulses, and its speed will oscillate $\pm$ the contact breaking speed. For small motors, the cycles of oscillation are so rapid that these $\pm$ variations are not discernible, 20 to 50 cycles occurring per second. Angular motion of the governor bars is then very small, in fact the motion at the contacts about 6/100 or 3/1000 of an inch, can be within the elastic deformation of the control lever. In case the motor drives parts which have much inertia or in case very low speeds are set, longer cycles result. It is clear that the external motor load must not slow the armature down below the speed set by the control knob, in other words, there can be no speed control unless the contact is active. Control knob 22 has its calibrated band member 22c marked in revolutions per minute, but it will be understood that other scale markings may be provided if so desired. A projection 28 on member 21 carries an indicator mark so that reference for the knob positions for any definite speed desired is given. The knob 22 may be oriented to shift the scale 22c in either direction with respect to the indicator 28 for orienting the calibrated scale to the desired position.

Larger motors require relay operation to handle heavy armature currents by means of a small governor to take care of arcing. The resultant motor speed does not absolutely conform to the knob setting, when the total work done by the motor varies over a wide range, hence the speed is then not quite proportional to the square of the spring torque, though the variation can be kept within $1/4\%$ for all loads. This limitation

does not apply to the use of the system for tachometers.

Figs. 10 and 11 show another form of contact. Here lever 30 corresponds to lever 14 of Fig. 1. Contact part 25 takes the form of a double brush 31, whereas part 27 is in the form of a cylindrical conductor 32 as shown. Pressed against 32 but separated by a small air gap and insulating mica washer 32a there is a cylindrical 10 guide 33. The brushes 31 just touch the part 32 when the motor is running at its normal speed. Rotatable screw device 34 on the adjusting screw 34a acts as a stop to lever 30 by abutment with insulation member 64. The brushes 31 move off 15 and on to conductor 32 with only a friction reaction on lever 30. If part 35 is arranged to oscillate or to turn, brush friction is decreased and the contact edge on brushes 31 much extended.

The control mechanism of my invention has been found highly practical in its construction and has a high degree of precision, and while I have described my invention in certain preferred embodiments I desire that it be understood that modifications may be made without departing from the spirit of my invention.

What I claim as new and desire to secure by Letters Patent of the United States is as follows:

1. In a device of the character described, a motor casing, a rotor in said casing having a shaft projecting from one end thereof, a housing extending from the said end of said casing, a yoke in said housing fixed to the projecting end of said shaft, a tube extending inwardly from the outer end of said housing in alignment with the shaft and yoke and having its inner end

spaced from the yoke, arms disposed in crossed relation to each other and pivoted at their intersection to said yoke with their end portions diverging from opposed side portions of the yoke towards inner and outer ends of the housing, a rod extending through said tube and projecting from the inner and outer ends thereof and provided with a head at its inner end, a sleeve slidably and rotatably fitting about said tube within the housing and having a chamber at its inner end disposed beyond the inner end of the tube about the head of said rod, bearing balls in said chamber between the head and walls of the outer portion of the casing to cause the sleeve and rod to move longitudinally together and facilitate rotation of the sleeve about the tube and rod, and links pivoted to opposed portions of said sleeve intermediate ends thereof and diverging inwardly from the sleeve and pivoted to adjacent ends of said arms.

2. In a device of the character described, a tubular supporting member, a sleeve concentrically disposed upon said tubular supporting member and rotatable and longitudinally adjustable thereon, said sleeve terminating in an enlarged cylindrical chamber forming a ball race, an actuating rod axially movable through said tubular supporting member, a head on the end of said rod disposed concentrically within said chamber, ball bearings between said head and the ball race in said cylindrical chamber and means for imparting sliding and rotatable movement to said sleeve and corresponding shifting said actuating rod in an axial direction.
